Edgar McFitchin,
his attorney.

UNITED STATES PATENT OFFICE.

GAYLORD A. BARCLEY, OF NEWARK, NEW JERSEY.

CORSET.

Application filed January 14, 1921. Serial No. 437,219.

To all whom it may concern:

Be it known that I, GAYLORD A. BARCLEY, a citizen of the United States, residing at Newark, in the county of Essex and State 5 of New Jersey, have invented certain new and useful Improvements in Corsets; and I do hereby declare the following to be full, clear, and exact description of the invention, such as will enable others skilled in the art 10 to which it appertains to make and use the same.

This invention relates to improvements in body garments, and more particularly to abdominal pads therefor and attachments 15 thereof.

Among the objects in view is the provision of a divided or sectional pad as distinguished from a one-piece pad and possessed of utility superior to a one-piece pad.

With these and other objects in view as will in part hereinafter become apparent and in part be stated, the invention comprises certain novel constructions, combinations and arrangements of parts as subsequently specified and claimed.

In the accompanying drawings,—

Figure 1 is a front view of a garment embodying the features of the present invention.

Figure 2 is an elevation of a fragment of the garment showing the manner of attachment of the pad-retaining straps.

Figure 3 is an elevation of the sectional pad detached, parts of the retaining straps 35 being broken away and a portion of the main section of the pad being turned back.

Figure 4 is a perspective view of a fragment of the main body of the garment illustrating one of the retaining buckles.

Figure 5 is a fragmentary, sectional view taken on the planes indicated by line 5—5 of Figure 2.

Referring to the drawings by numerals, 45 1 indicates the main garment which consists of the body of a corset or like article of apparel adapted to encircle the waist and abdominal areas of the wearer. The corset or main body 1 is opened at the front and provided with the usual hooks and eyes 2, 50 for securing the edges of the garment together along the opening. Adjacent the line of opening the garment is also formed with an opening laced as indicated at 3, for variations in the size and fit of the garment,

as is customary in apparel of this character. 55

Along the side portions in the body of garment 1 are arranged eyes 4 consisting, preferably, of elliptical or elongated openings formed through the body of the garment for the passage of pad-retaining strips 60 hereinafter mentioned. A vertical series of the eyes 4 is arranged along each side portion and each eye is preferably bound by metallic edging such as an appropriate grommet. Each of said grommets is slot- 65 shaped so as to conform to the transverse contour and proportions of the respective strap to be passed through the given eye 4. The material of garment 1 at the points where the grommets appear is of sufficient 70 thickness and stability to prevent the grommets from tearing out.

Within the garment 1 is arranged an abdominal pad consisting of two sections, one 75 of which I will designate as the main section 5 and the other as the supplemental section 6, the two sections being connected together by glove buttons or other appropriate connecting means 7, 7. To the free edge of section 5 are connected attaching straps 8, 8, and to the free edge of section 6 are connected similar straps 9, 9. An attaching strap 10 is connected to the main section 5 along the lower edge thereof for the full width of the section and extends beyond the side edges of the section a distance sufficient to serve as two attaching straps one 80 for each vertical edge of the pad. Thus the strap 10 extends past and overlaps the section 6, and the lower edge of the pad 5 85 is preferably tapered as best seen in Figure 3 with the strap 10 positioned to conform to such taper. The lowermost glove button 7 has its outer section connected not only through the section 5, but also through 90 the strap 10, so as to engage with and disengage from the section of the button carried by section 6 without being interfered with by the presence of the strap 10. 95

Along the outer surface of the garment 1 100 in the rear of each row of eyes 4 is attached a flap 11 to which are connected straps 12, 12, each carrying a buckle 13. It will be noted that there are as many buckles 13 105 for each flap 11 as there are eyes 4 at the respective side of the garment 1, and the buckles are arranged in line with the eyes so as to readily receive the straps 8, 9 and

10. It will also be noted that there are a greater number of eyes 4 and buckles 13 than there are attaching straps 8, 9 and 10, there being the equivalent of three attaching straps extending from each vertical edge of the abdominal pad made up of the sections 5 and 6. As the pad is arranged inside of the garment 1, the straps 8, 9 and 10 must be passed through eyes 4 to reach buckles 13 which are arranged outside of the garment, and the fact that there are more of the eyes and buckles than there are straps at each side enables vertical adjustment of the abdominal pad by the placing 15 of the pad with its straps in higher or lower eyes according to the location desired for the pad.

It is also to be noted that the strap 10 is particularly advantageously arranged for 20 receiving stresses and for delivering the weight and pressure of lower parts of the abdomen to the sides of the garment 1 and thence to the body of the wearer. Strain on the edges of the pad and on the sections between the straps 8 and 9 and the respective 25 sections of the pad, and also strain on the glove buttons 7 is largely eliminated or avoided by having such strains taken up directly by the strap 10.

30 In practical operation, the present improved garment is applied to the body of the wearer by having the garment opened along the line normally closed by the hooks and eyes 2 and by having section 5 in its proper position relative to the garment with the three straps 8, 8 and 10 extending through the eyes 4 and connected with the buckles 13, the section 6 being also in position with its straps 9, 9 passed through the 35 eyes 4 at the other side of garment 1 and connected to their respective buckles 13, the end portion of strap 10 at that side at which the section 6 appears being left disconnected and the sections 5 and 6 being left also disconnected. Thus the entire garment with its 40 pad being in an open position is placed bodily around the waist and abdomen of the wearer and the sections of glove buttons 7, 7 are snapped together for connecting the 45 sections of the abdominal pad. The free end portion of strap 10 is then passed through the proper eye 4 and laced into its respective buckle 13 and drawn to the tightened 50 position as desired by the wearer. The hooks and eyes 2 are then connected and the garment is in place. To remove the garment 1, it is only necessary to release the free end portion of strap 10 from its buckle at that 55 side where the straps 9 appear, to unhook the hooks and eyes 2, and open the buttons 7. Thereupon the garment may be drawn bodily away from the person of the wearer.

60 The abdominal pad thus constructed is especially well adapted for use in surgical cases, or in instances where it is desired to

provide support for the abdomen, as well as being effective in general use to restrain and confine the abdomen, the strain of such support or confinement being distributed to the hips and body of the wearer.

70 What is claimed is:

1. In a body garment, a pad comprising separable sections, quickly detachable means for connecting the sections together, an attaching strap for each section independent of the other section, and an attaching strap for one of the sections extending past the other section.

2. In a body garment, a pad comprising separable sections, quickly detachable means connecting the sections together, an attaching strap extending from one edge of one section, an attaching strap extending from the opposite edge of the other section, and an attaching strap connected to one section and extending from both edges thereof, one of the extensions of the last-named strap projecting past the other section.

3. In a body garment, a pad comprising separable sections, quickly detachable means connecting the sections together, attaching straps for the pad extending from the edges thereof, and an attaching strap extending entirely across and secured to the pad and projecting from both edges thereof, the last-named strap being attached to one of the sections only.

4. In a body garment, a pad comprising separable sections, quickly detachable means connecting the sections together, attaching straps for the pad extending from the edges thereof, and an attaching strap extending entirely across and secured to the pad and projecting from both edges thereof, the last-named strap being attached to one of the sections only and being located along the lower edge of the pad.

5. In a body garment, the combination with a corset body, of a sectional pad arranged therein, quickly detachable means connecting the sections of the pad together, attaching straps extending from opposite edges of the sections, an attaching strap extending across both sections and connected to one of the sections and having end portions extending away from the strap, the corset body being formed with eyes for the passage of the ends of the last-mentioned strap and the other attaching straps; and means for connecting the straps to the exterior portion of the corset body.

6. In a body garment, the combination with a corset body, of an abdominal pad within the corset body, having laterally extending attaching straps, the corset body being formed with eyes for the passage of the straps from the interior to the exterior of the corset body, strips fixed to and extending along the corset body and forming flaps, straps secured in the flaps and ex-

tending toward the first-mentioned straps, and attaching buckles for the first-mentioned straps carried by the second-mentioned straps, there being a greater number of eyes and buckles than first-mentioned straps for enabling adjustment of the abdominal pad along the corset body.

In testimony whereof I affix my signature in presence of two witnesses.

GAYLORD A. BARCLEY.
